Primary Examiner — Melanie Pellegrini

(74) Attorney, Agent, or Firm — Andrew F. Young, ESQ;
NOLTE LACKENBACH SIEGEL(57) **CLAIM**

The ornamental design for an adjustable ring as shown and described.

DESCRIPTION

FIG. 1 is rear, top, perspective view of an adjustable ring showing my new design.

FIG. 2 is a front, bottom, perspective view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a front elevation view thereof; and,

FIG. 8 is a rear elevation view thereof.

The dash-dash broken lines indicate portions that form no part of the claimed design. No claim is made to portions which are not shown.

1 Claim, 6 Drawing Sheets(56)
